UNITED STATES PATENT OFFICE.

WILLIAM KERBS KALLMAN, OF NEW YORK, N. Y., ASSIGNOR TO BLANCK & CO., INC., OF NEW YORK, N. Y., A CORPORATION OF NEW YORK.

DESIGN FOR LACE.

54,820.

Specification for Design.

Patented Apr. 6, 1920.

Application filed October 28, 1919. Serial No. 334,086. Term of patent 3½ years.

To all whom it may concern:

Be it known that I, WILLIAM KERBS KALLMAN, a citizen of the United States, residing at New York, in the county of New York and State of New York, have invented a certain new, original, and ornamental Design for Lace, of which the following is a specification.

Said design consists in a lace pattern as illustrated in the accompanying drawing, wherein the figure is a portion of a piece of lace showing my new design. The figure repeats indefinitely on the net in accordance with the length of the piece of lace.

What I claim as new is:

The ornamental design for lace as herein shown and described.

In witness whereof, I have hereunto set my hand and seal at New York, New York, this 25th day of October, A. D. nineteen hundred and nineteen.

WILLIAM KERBS KALLMAN. [L. S.]
